GEORGE A. MILANI, OF FRANKFORT, INDIANA.

Letters Patent No. 95,922, dated October 19, 1869.

IMPROVEMENT IN PROPELLING VESSELS.

The Schedule referred to in these Letters Patent and making part of the same

To all whom it may concern:

Be it known that I, GEORGE A. MILANI, of Frankfort, in the county of Clinton, and State of Indiana, have invented a new and improved Device for Propelling Vessels; and I do hereby declare that the following is a full, clear, and exact description thereof, which will enable others skilled in the art to make and use the same, reference being had to the accompanying drawing, forming part of this specification, in which—

Figure 1 represents a vertical longitudinal section of a boat, provided with my improved propelling-device.

Figure 2 is a plan or top view of the same.

Figure 3 is a vertical transverse section of the same.

Figure 4 is a detail face view of a spring, connected with the driving-gear wheel.

Similar letters of reference indicate corresponding parts.

This invention relates to a new mechanism for propelling small boats, life and flat-boats, and other small vessels; and consists in the general arrangement of machinery connected with an oscillating lever, that is worked by persons seated upon its ends.

The motion imparted to the lever by the see-sawing process, is transmitted to a pair of shafts, which are geared together with the paddle-wheel shaft.

Either of the driving-wheel shafts can be thrown out of gear at will, to allow steering by means of paddles.

A spring-connection is provided between each driving-shaft and its gearing, to produce greater regularity of motion.

A, in the drawing, represents a small vessel, of suitable form and construction.

In about the middle of its sides are the bearings of a pair of paddle-wheel shafts, B B, which carry the paddle-wheels C at their ends.

These shafts are made entirely separate from, but are in line with each other, as is clearly shown in fig. 3.

They need not reach far into the boat, no further than necessary to accommodate pinions *a a* that are mounted upon them.

Under the shafts B are hung in the boat the two driving-shafts D D, which have their bearings in studs *b*, that project from the inside of the boat, as shown in fig. 3.

The shafts D are also in line with and separated from each other, as shown.

Each of them carries a ratchet-wheel, *c*, near its inner end.

A toothed wheel, E, is hung loose upon each shaft, D, and meshes into the pinion *a a* above it.

Each toothed wheel E is connected with its shaft D by means of a coiled spring, *d*, as shown in fig. 1, so that when the shaft is turned in the direction of the arrow 1 in fig. 1, the wheel will, by the same, be carried around in the same direction.

The spring will equalize the motion so that the boat will move with ease and regularity.

Instead of the coiled springs *d*, straight spring-arms, *e e*, may be employed, as in fig. 4, for connecting the shafts D with the wheels E.

The flat spring-arms *e* will answer better for larger boats, as they will be stronger than the coiled spring.

On the upper end of a post, *f*, that projects from the bottom of the boat, is the fulcrum *g* of a lever, F, which lever extends longitudinally nearly to the ends of the boat.

To both sides of the fulcrum-pin *g*, are arranged up-and-down projecting arms, *h*, on the lever, which carry on each side of the lever a pair of pawls, *i j*.

Each pair of these pawls catches into the teeth of one of the ratchet-wheels, one pawl in front and one in rear of the axle D, so that as the lever is swung on its pivot, the ratchet-wheels will be turned, whatever be the motion of the lever.

The teeth of both ratchet-wheels are in the same direction, and are of equal number, so that both shafts D will at once be turned with equal velocity.

Upon the ends of the lever F are arranged seats G.

A person is to be seated on each end of the lever, and by see-sawing the same, the shafts D, and, with them, the shafts B, will be turned.

H H are levers pivoted to the studs *b*, or otherwise, and extending toward the stern of the boat.

These levers H have upward projections, with cross-arms, K, that are raised when the outer ends of the levers are lowered.

Each cross-bar K will, when raised, elevate one pair of pawls off its ratchet-wheel, and will thereby throw one of the paddle-wheels out of gear while the other will remain in motion. The boat can thus be steered.

The central plate, from which the flat springs *e* radiate, may be notched to receive pins projecting from the driving-wheels, for the purpose of preventing the overstraining of the springs, and for getting more direct action from the driving-shafts.

Having thus described my invention,

What I claim as new, and desire to secure by Letters Patent, is—

1. The combination of a centrally-fulcrumed lever, having a seat at each end, with two pairs of pawls and ratchet-wheels, arranged as described, to rotate

two aligned shafts, D D, simultaneously and with equal velocity, as set forth.

2. The arrangement, on a boat, of two aligned shafts, D D, rotating with equal velocity, spur-wheels E E, pinions a a, and shafts B B, to propel the paddle-wheels C C, in the manner described.

3. The arrangement, upon the paddle-driving shaft D D of a boat, of loose equalizing spring spur-wheels E E, for the purpose of giving a uniform motion to the paddle-wheels.

4. The arrangement, near the bottom of the boat, of a lever, H, fulcrumed and shaped as described, for the purpose of removing the pawls from the ratchets, in the manner specified.

GEORGE A. MILANI.
